UNITED STATES PATENT OFFICE

ALEXANDER DOW, OF NEW YORK, N. Y., ASSIGNOR TO DOW PATENTS HOLDING CORPORATION, A CORPORATION OF DELAWARE

STARTER MECHANISM FOR ENGINES

Application filed May 22, 1930. Serial No. 454,566.

This invention relates to starting mechanism for internal combustion engines, and more particularly to starting mechanisms of the friction type.

The invention claimed in this application is an improvement on an invention described in an application for patent now pending in the U. S. Patent Office, the same bearing Serial No. 452,502, filed May 14, 1930. In said pending application I describe and specifically claim a starter of the inboard bearing type. The present application is directed to friction starters of the outboard bearing type.

It is deemed desirable in presenting the present application for patent that the specification and drawings of said pending application be reproduced herein and made part hereof, which taken in connection with additional description, drawings and claims, will fully present the invention covered by this application for patent.

The following is a copy of said application for patent, omitting the claims made in that application.

This invention is a starter mechanism for internal combustion engines and is of that general type wherein a pair of cooperating gripping members are adapted to frictionally grip and drive an interposed driven member, usually in the form of a ring carried by the crank shaft or fly wheel of an engine.

The primary object of the invention is to provide a starting mechanism of the character described wherein the parts entering into the construction may be more economically manufactured and assembled than heretofore. This is accomplished by mounting all of said parts directly upon the driving shaft of the starting mechanism in such sequence that they will cooperate to cause the gripping members to engage with and drive the driven member during starting operations and to free the gripping members from contact with the driven member at all other times.

Thus, in one of its preferred practical forms, the starting mechanism of this invention embodies a driving shaft suitably

mounted to rotate and adapted to be driven from an appropriate prime mover, and on this shaft the several parts are coaxially assembled in the following sequence, to wit:— first, a fixed collar rigidly secured by a pin, 55 or otherwise, to the shaft to rotate therewith; next, a loose sleeve free for rotation and longitudinal sliding movement on the shaft, the adjacent ends of the collar and sleeve having gripping faces to engage an interposed driven member, and the loose sleeve having at its opposite end a cam face; next, a cam follower, keyed to slide longitudinally on the shaft and rotate therewith; and, lastly, an adjusting element which may conveniently be a nut threaded on the shaft. All of these elements are directly mounted on the shaft and individually depend upon the shaft for support. 65

Another object of the invention is to provide, in a starting mechanism of the character described means which will, under normal conditions, function as a substantially rigid strut to hold the gripping members in driving engagement with the driven member 70 during starting operations but which means, nevertheless, has the characteristic that, under abnormal conditions, said means will resiliently yield while maintaining the desired driving engagement between the parts. 75 The said means is preferably in the form of a spring normally held by an appropriate retainer under a predetermined minimum compression sufficiently high to cause said spring to be substantially neutral under ordinary operating conditions, but sufficiently low to permit the spring to resiliently yield under abnormal conditions. This spring may be conveniently introduced into the assembly hereinbefore described, by interposing it somewhere between the adjacent element and the gripping face of the loose sleeve. In practice, it is, by preference, positioned between said adjusting element and the follower. 85

A further feature resides in the means whereby the gripping members are both normally maintained free from contact with the ring, except when the gripping members are actually driving said ring. 90

Features of the invention, other than those specified, will be apparent from the herein-after detailed description and claims, when read in conjunction with the accompanying 5 drawings.

The accompanying drawings illustrate different practical embodiments of the invention, but the constructions therein shown are to be understood as illustrative, only, and not 10 as defining the limits of the invention.

Figure 1 is a plan view of engine starter mechanism embodying the present invention. In this view a portion of the fly wheel and associated ring are shown in section.

15 Figure 2 shows the same construction as illustrated in Figure 1, but with the shaft rotated through 90 degrees and the gripping members in engagement with the driven member. In this view, certain of said parts 20 are shown in central section in the interest of clearness.

Figure 3 is a diagrammatic view showing the development of the loose sleeve and the cam surfaces thereon.

25 Figure 4 is a view corresponding to Figure 1, but showing, as an added element, resilient means interposed between the yoke and the adjusting nut to provide for the elastic engagement of the gripping members with the 30 ring of the fly wheel.

Figure 5 shows the same construction as illustrated in Figure 4, but with the shaft turned through 90 degrees and with the gripping members in engagement with the driven 35 member. In this view, certain of the parts are shown in central section in the interest of clearness.

Figure 6 shows an entire starter motor assembly embodying the present invention in 40 elevation.

Figure 7 shows a modified form starter assembly also embodying this invention and with certain parts illustrated in central section.

45 Referring to the drawings, and more particularly to Figures 1 and 2, 1 indicates a bearing which may be one of the end bearings of the casing of a starting motor. This motor may be of any conventional form and 50 is provided with an armature shaft 2 extending beyond the casing a sufficient distance to accommodate the parts which, according to the present invention, are associated therewith. Directly secured to the armature shaft adjacent the housing 1 is one friction member 3 of the assembly. This friction member is in the form of a collar firmly secured to the shaft 2 by means of a pin 4 or in any other suitable manner.

60 Arranged further along the shaft and having a rotatable and sliding fit on the shaft is a sleeve 5 which constitutes the other gripping member. The contiguous faces of the gripping members 3 and 5 carry the gripping 65 faces 6 and 7 and these faces are preferably

of conical form, whereby they are adapted to cooperate with and grip the interposed ring 8 of an engine fly wheel 9. A spring 10 is preferably interposed between the members 3 and 5 and serves to force these members apart. The slight lost motion commonly found in armature shafts of conventional motors will permit freeing of the face 6 from engagement with the ring 8 of the fly wheel, as herein-after more fully explained. 70

The end of the element 5 opposite to that which carries the gripping face 7 is formed with cam surfaces designated generally by the reference character 11 and herein-after more fully described and with these cam faces is adapted to cooperate a cam follower. The follower is in the form of a yoke having a sleeve 12 which has a close sliding fit with the shaft 2 and is keyed against rotation thereon by means of a key 13. The sleeve 12 carries at its inner end two arms 14, and these two arms each carry a roller 15 which coacts directly with a cam surface 11. The rollers each have a trunnion 16 and each arm 14 is perforated to form a bearing for the trunnion of the associated roller. 75

The outer end of the shaft 2 is threaded as shown at 17 and on to this threaded portion of the shaft beyond the follower is screwed a castellated or slotted nut 18. The shaft is 80 perforated or slotted and a cotter pin 19 is adapted to be passed through the castellations of the nut 18 and through the perforation or slot of the shaft to lock the nut 18 in adjustment. 90

In practice, the starter is mounted in proximity with the engine which it is adapted to crank and is so positioned that the ring 8 of the flywheel will project between the gripping faces 6 and 7. The nut 18 is thereupon regulated to adjust the relative position between the parts of the starter with reference to said ring which serves as a gauge for such adjustment. 100

105 While the cam faces 11 to which I have referred may vary without departing from this invention, they preferably, as indicated in Figure 3, each embody a depressed seat 20. From one side of each depressed seat, the cam surface rises gradually as indicated at 21, and this gradual rise terminates in an abrupt ascent indicated at 22, which is preferably in the form of an arc, the radius of which is substantially the radius of the roller cooperating therewith. As a result of this construction, the rollers will normally occupy the depressed seats 20 and when in this position the spring 10 will be free to force the gripping members apart. 115

120 When the starting motor is energized and the shaft 2 rotated with rapid acceleration, the followers advance out of the depressions or seats 20 on to the gradual rising portion 21 of the cam faces and continue to so rise 125 for the purpose of forcing the gripping mem- 130

ber 5 into engagement with the fly wheel ring and simultaneously reacting to draw the gripping member 3 into engagement with the opposite side of said ring 8. This operation 5 will proceed until the rollers engage the rapid ascents 22 of the cam faces which ascents will constitute, in effect, stops to the further travel of the rollers over the cam faces, but the nut 18 is so adjusted that the engagement of the 10 rollers with the stops of the cam faces will occur simultaneously with the establishment of frictional driving engagement between the gripping members and the fly wheel ring 8.

When the engine starts and gathers sufficient speed to impart to the ring 8 a speed greater than the normal driving speed of the starting motor, the ring 8 will thereupon rotate the gripping member 5 at a speed greater than the speed of the armature shaft and 20 cause the cam faces 11 to advance away from the cam follower. By this operation, the cam follower will be caused to roll down the cam faces to bring the rollers into the depressions or seats 20 and to thereby release the fly wheel 25 ring from the gripping action of the members 3 and 5.

The structure shown in Figures 4 and 5 is, in the main, substantially the same as that illustrated in Figures 1 and 2 with the addition of certain parts. Thus, it will be noted that the structure of Figures 4 and 5 embodies a bearing 1 for the shaft 2. The fixed gripping member 3 is secured to the shaft by the pin 4, while the gripping element 5 is loose 35 on the shaft and cooperates with the member 3 to grip and drive the ring 8. The outboard end of the gripping member 5 has cam faces engaged by the rollers 15 carried by the arms 14 of the yoke and the yoke is provided with 40 a sleeve 12 having a keyed connection 13 with the shaft 2. A nut 18 of castellated or slotted character is screwed on to the end of the shaft 2 and serves to adjust the yoke longitudinally of the shaft.

It will be noted, however, that the nut 18 instead of acting directly against the sleeve of the yoke coacts with said sleeve through an intermediate spring 23 which is interposed 50 between the nut and the yoke, so that as the cam follower reacts against the nut 18, it does so through the interposed spring 23.

In practice, this spring may be of any suitable character and may coact with the parts in various ways for the carrying out of the 55 purposes stated. Nevertheless, the form of construction shown in the drawings has been found to give highly satisfactory results and is preferred. Here the spring is shown of the helical type enclosed within an annular 60 band or sleeve 24 of tubular section. In the opposite ends of the tubular section are washers 25 and 26 and the opposite ends of said section are spun over the outer faces of the washers to form a substantially closed 65 cage in which the spring is housed. I may

make the cage in other ways than as described, but the form shown is efficient and economical.

I have also found it highly desirable to house the spring within the cage with the 70 spring under a predetermined minimum compression which is appreciable. While this is not absolutely essential, it is highly desirable. Suppose, for example, that under ordinary driving conditions a pressure of say 75 α pounds is required to be exerted by the gripping members upon the ring, then I prefer that the normal compression of the spring within the cage be somewhat in excess of α pounds, so that under normal conditions 80 of driving where the thickness of the ring is uniform throughout, the spring will be to all intents and purposes neutral and the pressure of the gripping members upon the ring will be positive. If, however, the ring 8 85 varies appreciably in thickness at different parts of its circumference or for other reasons a yielding of the gripping members in an axial direction is required, then, and in that event, the spring will yield when subjected to 90 the increased reaction of the cam follower or to the action of the nut transmitted to said nut through the shaft from the member 3, and the gripping members will continue to drive the ring in an efficient manner. 95

Another advantage of having the spring within the cage and which renders this construction the preferred construction is that the spring while under a predetermined minimum compression is adjustable longitudinally 100 of the shaft to effect desired adjustment of the cam follower through rotation of the nut 18 without varying the normal tension of the spring.

It will of course be understood that the 105 washers 25 and 26 are movable toward one another within the cage, so as to permit compression of the spring as stated. As shown in Figures 4 and 5, the sleeve 12' of the yoke is of reduced cross section for a portion of its 110 length, so as to permit it to extend into the interior of the spring. The purpose of this arrangement is to minimize the length of the device, although so far as the operation is concerned the spring and cage unit might be 115 interposed directly between the sleeve 12 and the nut 18 of Figure 1 if the shaft were made somewhat longer.

It is to be noted that while the structure 120 of Figures 4 and 5 contemplates the employment of the spring as stated, the spring with its associated cage and washers may be entirely removed and the nut 18 screwed, so as to cooperate directly with the end of the sleeve 12'.

The springs 10 of Figures 1, 2, 4 and 5 serve to normally maintain the gripping members in separated relation with the cam rollers 15 in the depressions 20. This is the normal condition of the parts and they remain so until 130

it is desired to employ the starting mechanism to crank the engine with which the ring 8 is associated. When the starting motor is energized, the shaft 2 together with the gripping member 3 and cam follower are separated and speeded up with rapid acceleration, while the inherent inertia of the gripping member 5 causes it to lag. There results a relative rotation between the cam follower and the member 5 which causes the rollers 15 to ride upon the cam surfaces of the member 5 and thereby force said member 5 into engagement with one face of the ring 8. A reactionary force acts through the cam follower to the shaft 2 and serves to draw said shaft in a direction to move the gripping element 3 into engagement with the other face of the ring 8 and thus these two forces cooperate to cause the ring 8 to be tightly gripped between the gripping members 3 and 5, so that upon continued rotation of the parts which are carried by said shaft, the gripping member 5 will rotate therewith, while the members 3 and 5 will drive the ring 8 for the purpose of cranking the engine. This operation will continue until the engine has been started and commences to operate under its own power whereupon the ring 8 will be driven from the engine at a greater speed than the speed of the gripping members 3 and 5.

The drag of the armature upon the shaft 2 and member 3 will thereupon tend to slow down the operation of the gripping member 3, while the gripping member 5 will tend to travel at the speed of the ring 8 and consequently the member 5 will travel faster than the cam rollers 15 and they will be caused to partake of retrograde movement down the cam surfaces and be returned into the depressions 20 for the purpose of separating the gripping members from driving relation with the ring 8.

The spring 10 will separate these members 3 and 5 during its operation, but it is of considerable importance that the members be also separated from contact with the ring 8, because if one of them continues to contact with this ring, undesirable wear and abrasion will result. Various means may be employed for insuring this latter separation. In Figure 6, a very satisfactory and practical arrangement is illustrated. Here the bearing 1 is shown as one of the end bearings of the armature shaft of a starting motor 27, the opposite end bearing of which is designated 28. The shaft 2 is extended beyond the bearing 28 and carries a fixed collar 29. A spring 30 is interposed between the collar 29 and the bearing 28 and serves to normally move the armature shaft 2 to the left. This movement is limited by engagement of the gripping member 3 with the adjacent end of the bearing 1. Thus, when the motor is de-energized, the gripping member 3 is disengaged

from the ring 8 by the power of the spring 30, while the spring 10 will force the member 5 in the opposite direction to free it from contact with said ring. In this way, both elements are normally maintained free from contact with the ring 8 in a simple and efficient manner. It will be understood, however, that when the starting motor is energized to carry out an engine starting operation, the action between the cam follower and the cam face of the member 5 will become a predominating force well able to overcome the power of the spring 30 and entirely effectual to force the members 3 and 5 into driving engagement with the ring 8.

The arrangement shown in Figure 6 is particularly adapted for use with electric starting motors, but the invention of course is not limited to use with such motors, for any suitable source of power may be utilized for cranking purposes. Thus, as shown in Figure 7, the shaft 2 is mounted in an appropriate bearing 1, back of which a collar 31 is fixed to the shaft and between the collar 31 and the bearing 1 is interposed a spring 32 which functions in the same manner as the spring 30 of Figure 6. The end of the shaft 2 is square as indicated at 33 and extends into a square socket 34 associated with the main power shaft 35 driven from any suitable prime mover. The squared connections 33 and 34 permit of longitudinal movement of the shaft 2 to allow the member 3 to be engaged with or disengaged from the ring 8. As is well known, there is sufficient end play in the armature shaft of an electric motor such as shown in Figure 6 to permit of a like movement.

In practically carrying out this invention, the springs 30 and 32 of Figures 5 and 6 may be positioned as shown in these figures or may operate in the same direction upon the shaft by acting through a center pin at the outboard end of the shaft 2 in either case. These details of construction are optional and the present invention is not confined to the specific detailed construction shown.

The various forms of the invention which are hereinbefore described and shown in the accompanying drawings embody numerous novel features, all of which are directed to the production of a starter of marked simplicity and efficiency and one susceptible of satisfactory quantity production with expeditious assembly and a minimum of subsequent surfacing. As stated, the spring between the yoke and adjusting nut is preferred though not essential. This preference rises out of the numerous advantages which its presence provides.

The drawings show the invention in its preferred practical forms, but the invention is to be understood as fully commensurate with the appended claims.

The following additional drawings are

supplied for the purposes of this case, in which the several parts are designated by numerals, like numerals referring to like parts. The difference in structure and operation will be pointed out as we proceed.

Figure 8 is a plan view of starting mechanism of the outboard bearing type, according to the present invention, showing the gripping members which are adapted to grip and drive the interposed driven member disengaged from the latter member. In this view, certain parts are illustrated in section in the interest of clearness.

Figure 9 is a view showing the same parts illustrated in Figure 8, but with the drive shaft rotated through 90 degrees and certain of the parts shown in central section. This view also shows the gripping members in engagement with the interposed driven member.

Figure 10 is a diagrammatic view showing the development of one of the loose sleeves which is provided at one end with a cam surface to coact with follower rollers also shown in this figure.

Figure 11 shows the starter with an added element.

In application Serial Number 452,502, filed May 14, 1930, the specific form of starter mechanism which I chose to show for the purpose of illustration was of the inboard bearing type, i. e., the type wherein the friction starting mechanism was mounted upon a shaft which extended from appropriate bearings into space, such, for example, as an extension of the armature shaft of an electric starting motor. The present invention relates to starting motors of the same general character, but embodying an outboard bearing; that is to say, a construction wherein the driving shaft is supported at both ends with the friction drive mechanism carried by the shaft intermediate the supporting bearings of the latter.

The object of the present invention is to provide a simple and efficient friction starter mechanism adapted to be mounted upon a shaft having bearings at both ends of the friction starter mechanism.

Referring to Figures 8, 9 and 10 of the drawings, 1 and 23 indicate bearings to support the shaft 2 which constitutes the driving shaft. The bearings 1 and 23 may be supported in any suitable way, but of the source of power is an electric motor, the motor housing may serve to support the bearing 1, and an arm or bracket 24 may extend from the motor housing to support the bearing 23.

The shaft is mounted to rotate freely in these bearings 1 and 23, and is preferably stepped down as illustrated in Figure 9 to provide three distinct portions 25, 26 and 27 of different diameters, which are progressively smaller to facilitate assembly of

the parts. The portion 27 extends into and is supported for rotation within the bearing 23. On the portion 26 the several operating elements of the structure are supported in sequence. That is to say, the gripping member or fixed collar 3 is mounted near the outboard board end of the portion 26 directly adjacent the bearing 23 and is secured to the shaft to rotate therewith in any suitable manner as by a pin 4. The loose sleeve 5 is mounted on the portion 26 in spaced relation to the collar 3, and is loose on the shaft, i. e., it is free to rotate thereon and also free to longitudinally slide thereon. The contiguous ends of the gripping members 3 and 5 are provided with the gripping faces 6 and 7 which are preferably though not necessarily of conical form and these faces are adapted to cooperate with and grip the ring or annular member 8 which is formed on or carried by the fly wheel 9.

Positioned next in sequence on the shaft 3 is the cam follower 12 in the form of a yoke. The hub of the yoke is bored to embrace the portion 26 of the shaft with a sliding fit, and the key 13 cooperates with the yoke to secure it for rotation with the shaft.

The yoke has arms 14 and 14 in which are formed bearings 28 and within the confines of the yoke are the rollers 15. Each of these rollers carries a trunnion 16 and these trunnions engage with the bearings 28 to mount the rollers on the yoke. The rollers are adapted to cooperate and coact with the cam faces 11 formed on the adjacent end of the loose sleeve 5, as will be readily understood.

A spring 10 is interposed between the gripping members 3 and 5 and this spring serves to normally separate said members and hold them free from contact with the driven member 8 and at the same time hold the cam faces 11 in engagement with the rollers 15.

The portion 25 of the shaft is threaded as shown at 17a in Figure 9 and on this portion of the shaft is positioned the adjusting nut 18 which is adapted to be longitudinally adjusted with reference to the threads for the purpose of regulating the position of the yoke longitudinally of the shaft in order that the parts may be adjusted, so that in operation an appropriate satisfactory gripping cooperation may be had between the gripping members 3 and 5 and the driven member 8.

Figures 8 and 9 of the drawings show the nut 18 coacting directly with the follower 12, but I wish it understood that if desired I may interpose between the follower 12 and the adjusting nut 18 a yieldable element such as the spring 23 and its associated cage 24 shown in Figures 4-7, inclusive, and described in connection with these figures.

Figure 11 shows this construction.

The nut 18 is of slotted or castellated form as indicated and the shaft is perforated as

shown at 19, so that a cotter pin or other appropriate locking device may be inserted through the castellations of the nut and the perforation in the shaft to lock the nut in adjustment.

The cam faces 11, as employed in Figures 8 and 9, are shown in Figure 10. It will be noted that they are here illustrated as substantially the same as in Figure 3, with the exception that they are reversed to compensate for the inverse relation of the elements on the shaft. I do not consider it necessary to describe the particular contour or formation of these cam faces 11, as they are fully described and claimed in my applications, Serial Nos. 226,170 and 293,731. The cam faces may be formed as disclosed in either of these applications or in any appropriate manner without departing from this invention.

The parts illustrated in Figures 8, 9 and 10 of the drawings operate the same as in the previous figures, to wit: Under normal conditions, the relation of the parts is as indicated in Figure 8 with the gripping faces 6 and 7 free from engagement with the driven member 8. When it is desired to start the engine, the shaft 2 is rotated with rapid acceleration. As the shaft turns, it carries with it the fixed collar 3, the cam follower 12 and the adjusting nut 18. The loose sleeve 5, however, by virtue of its inherent inertia, lags sufficiently to cause the rollers 15 to ride upon the cam face 21 and thus force the loose sleeve 5 longitudinally of the shaft and into engagement with the driven member 8. The cam follower reacts to longitudinally shift the shaft 2 to the left for the purpose of drawing the fixed collar 3 into engagement with the driven member, and as both gripping members engage with the driven member, the rollers and cam faces coact to bring about a sufficiently tight gripping cooperation as will insure the driving of the member 8 by the gripping members. This driving of the member 8 continues until the associated engine starts. When the engine gathers sufficient speed to impart to the member 8 a speed greater than the normal driving speed of the starting motor, the cam rollers 15 will be caused to roll down the cam faces and permit the gripping members to return to the normal positions of Figure 8, wherein the faces 11 and 12 are out of contact with the member 8.

The structure which has been described is economical to manufacture, thoroughly efficient for its intended purposes and may be assembled, dismantled or adjusted in a ready and expeditious manner. There are practically no parts to get out of order.

The foregoing detailed description sets forth the invention in its preferred practical form, but the invention is to be under-

stood as fully commensurate with the appended claims.

Having fully described the invention, what I claim as new and desire to secure by Letters Patent is:

1. A starting mechanism for internal combustion engines, embodying a shaft, means at one end of the shaft for driving the same, spaced apart inboard and outboard bearings to support the shaft, and a plurality of driving elements arranged in the following sequence on said shaft between the inboard and outboard bearings:—the first element being a member longitudinally adjustable on the shaft adjacent the inboard bearing for adjusting the relative position of the succeeding elements; the next element being a cam follower mounted for rotation with and for longitudinal sliding movement on said shaft; the next element being a loose sleeve free for rotation and longitudinal sliding movement on the shaft and provided at its end adjacent the follower with cam faces to cooperate therewith, said loose sleeve having a gripping face at its other end; the next element being a collar fixed on the shaft adjacent the outboard bearing and having at its inner end a gripping face adapted to cooperate with the gripping face of the loose sleeve to grip and drive an interposed driven member; and a driven member interposed between said gripping faces.

2. A starting mechanism for internal combustion engines, embodying a shaft, means at one end of the shaft for driving the same, spaced apart inboard and outboard bearings to support the shaft, and a plurality of driving elements arranged in the following sequence on said shaft between the inboard and outboard bearings:—the first element being a member longitudinally adjustable on the shaft adjacent the inboard bearing for adjusting the relative position of the succeeding elements; the next element being a cam follower mounted for rotation with and for longitudinal sliding movement on said shaft; the next element being a loose sleeve free for rotation and longitudinal sliding movement on the shaft and provided at its end adjacent the follower with cam faces to cooperate therewith, said loose sleeve having a gripping face at its other end; the next element being a collar fixed on the shaft adjacent the outboard bearing and having at its inner end a gripping face adapted to cooperate with the gripping face of the loose sleeve to grip and drive an interposed driven member; a driven member interposed between said gripping faces; and a resilient member interposed between the adjusting member and the gripping face of the loose sleeve.

3. A starting mechanism for internal combustion engines, embodying a shaft, means at one end of the shaft for driving the same, spaced apart inboard and outboard bearings

to support the shaft, and a plurality of driving elements arranged in the following sequence on said shaft between the inboard and outboard bearings:—the first element being a member longitudinally adjustable on the shaft adjacent the inboard bearing for adjusting the relative position of the succeeding elements; the next element being a resilient member; the next element being a cam follower mounted for rotation with and for longitudinal sliding movement on said shaft; the next element being a loose sleeve free for rotation and longitudinal sliding movement on the shaft and provided at its end adjacent the follower with cam faces to cooperate therewith, said loose sleeve having a gripping face at its other end; the next element being a collar fixed on the shaft adjacent the outboard bearing and having at its inner end a gripping face adapted to cooperate with the gripping face of the loose sleeve to grip and drive an interposed driven member; and a driven member interposed between said gripping faces.

4. A starting mechanism for internal combustion engines, embodying a shaft, means at one end of the shaft for driving the same, spaced apart inboard and outboard bearings to support the shaft, and a plurality of driving elements arranged in the following sequence on said shaft between the inboard and outboard bearings:—the first element being a member longitudinally adjustable on the shaft adjacent the inboard bearing for adjusting the relative position of the succeeding elements; the next element being a spring with means to normally hold it under a predetermined minimum compression; the next element being a cam follower mounted for rotation with and for longitudinal sliding movement on said shaft; the next element being a loose sleeve free for rotation and longitudinal sliding movement on the shaft and provided at its end adjacent the follower with cam faces to cooperate therewith, said loose sleeve having a gripping face at its other end; the next element being a collar fixed on the shaft adjacent the outboard bearing and having at its inner end a gripping face adapted to cooperate with the gripping face of the loose sleeve to grip and drive an interposed driven member; and a driven member interposed between said gripping faces.

5. A starting mechanism for internal combustion engines, embodying a shaft, means at one end of the shaft for driving the same, spaced apart inboard and outboard bearings to support the shaft, and a plurality of driving elements arranged in the following sequence on said shaft between the inboard and outboard bearings:—the first element being a nut having threaded engagement with the shaft adjacent the inboard bearing for adjusting the relative position of the succeeding elements; the next element being a cam fol-

lower mounted for rotation with and for longitudinal sliding movement on said shaft; the next element being a loose sleeve free for rotation and longitudinal sliding movement on the shaft and provided at its end adjacent the follower with cam faces to cooperate therewith, said loose sleeve having a gripping face at its other end; the next element being a collar fixed on the shaft adjacent the outboard bearing and having at its inner end a gripping face adapted to cooperate with the gripping face of the loose sleeve to grip and drive an interposed driven member; and a driven member interposed between said gripping faces.

Signed by me at New York city this 20th day of May, 1930.

ALEXANDER DOW.
